UNITED STATES PATENT OFFICE

WILLIAM C. JAY, OF PHILADELPHIA, PENNSYLVANIA, ASSIGNOR TO SANITARY PRODUCTS CORPORATION OF AMERICA, OF PHILADELPHIA, PENNSYLVANIA, A CORPORATION OF VIRGINIA

SAFETY DEVICE FOR DIE PRESSES

Application filed May 15, 1929. Serial No. 363,124.

This invention relates to machines for forming articles from sheet material, such as machines for forming plates and the like from paper or similar non-conductive stock.

5 The invention is directed particularly to machines of this type wherein the sheet material, usually in the form of a continuous web, is fed between relatively movable die members adapted to cooperate to cut and 10 stamp an article from the sheet material, leaving the perforated web which is removed from engagement with the dies and returned to its normal position by a resilient stripper plate. The perforated web 15 is somewhat difficult to handle and is apt to pile up between the die members and interfere with the proper operation of the machine. The web often breaks and clogs the dies, causing damage to the stock and, in 20 some instances has caused breakage of the dies before any irregularity of the operation of the machine has been discovered.

Furthermore, serious trouble is sometimes caused by failure of the sheet material to 25 be fed properly from the feed rolls over the dies. This may be caused by defective stock, but more frequently by failure of the stripper plate to lift the stock clear of the dies. Failure of the stripper plate to function properly may be caused by a broken 30 stripper plate spring, or by a raw edge or "whisker" being pulled down between the dies and stripper plate as a result of the dies becoming dull or slightly out of alinement. 35 In such instances, on account of the frequency and relatively quick speeds and long distances that the stock is fed at each cycle of the machine or press, the stock of sheet material may double under the stripper 40 plate and over the dies for several laps and build up a sufficient thickness of stock to result in injury to the machine.

It is an object of the invention to overcome these difficulties and provide a mechanism which will disconnect the power and stop the machine automatically if the sheet material is not fed or advanced properly through the machine.

Before explaining in detail the present 50 invention, it is to be understood that the

invention is not limited in its application to the details of construction and arrangement of parts illustrated in the accompanying drawing, since the invention is capable of other embodiments and of being practised 55 or carried out in various ways. Also it is to be understood that the phraseology or terminology employed herein is for the purpose of description and not of limitation, and it is not intended to limit the invention 60 beyond the terms of the several claims here-to appended as considered in view of the prior art and the requirements thereof.

The invention will be more clearly understood from the following description in conjunction with the accompanying drawing, which is a diagrammatic elevational view 65 of a machine embodying the invention.

While the invention is applicable to die presses and similar machines of a wide variety of forms and types, it is herein shown for illustrative purposes as applied to a press for blanking out and forming plates from a web of paper stock. The frame of the press illustrated comprises a suitable 70 base 10 and side uprights 11 supporting between them the bed 12 and having guides 13 for the cooperating ram 14. The complementary upper and lower combined blanking out and forming dies 15 and 16 75 are carried by the ram and bed respectively, the lower dies 16 having associated therewith the usual spring supported stripper plate 17. The main operating shaft 18 of the press is journalled in the uprights 11 and 80 is provided with suitable means for reciprocating the ram 14 in the guides 13 toward and from the bed 12, said means as herein shown comprising a cam 19 cooperating with a cam follower 20 on a stem 21 projecting 85 upwardly from the ram, said cam follower being held in engagement with said cam by springs 22 connecting the ram with a cross head 23 suitably supported from the frame side members 11 above the upper ends of 90 the latter.

The stock, in the form of a web W of paper or other electrically non-conductive material, is intermittently fed between the dies by mechanism herein shown as a pair 100

of intergeared feed rollers 24 one of which is connected by one-way clutch 25 with a pinion 26 meshing with a rack 27 suitably connected at its upper end with the ram 14, the arrangement being such that as the ram rises away from the bed the web will be advanced and as said ram descends toward the bed the web will remain stationary.

10 Suitable means are provided for applying power to the shaft 18 to rotate the same, said means as shown comprising a power shaft 28 journaled in brackets 29 carried by the frame uprights 11, said power shaft having a pulley 30 to which power from any suitable source may be transmitted through a belt 31 and a second pulley 32 connected by a belt 33 with a pulley 34 on the shaft 18. The power transmitting connections between the pulleys 30 and 32 through the shaft 28 include a clutch 35 operated by a clutch fork 36 whereby the shaft 18 may be connected with and disconnected from its source of power. The clutch fork 36 is formed on one arm of the bell crank 37 the other arm of which is connected by a rod or link 38 with a treadle or operating lever 50 suitably pivoted at 51 to the base 10 of the frame. The treadle 50 is normally held by a spring 52 in the elevated position shown in dotted lines to cause the clutch fork 36 to release the clutch 35, thereby disconnecting the shaft 18 from its source of power and stopping the press. When depressed into the full line position the treadle 50 operates through the connections described to close the clutch 35, thereby connecting the shaft 18 with its source of power and starting the press. Said treadle may be locked in the last named position to maintain the press in operation by a toggle 53 connecting said treadle with a suitable part of the frame.

45 Except as hereinafter pointed out, or as they enter into combination with the mechanism hereinafter described, the parts above referred to specifically form no portion of the present invention and may be of any usual or suitable construction and arrangement. In accordance with the present invention means are provided for automatically unlocking the treadle or operating lever 50 upon failure of the web W. For this purpose as illustrated, a solenoid is positioned adjacent the toggle 53 and has its windings 60 connected in an electric circuit 61 of relatively high potential, such as a 110 volt line. A plunger 62 enclosed by the windings 60 of the solenoid is arranged to 55 be operated by said solenoid, when the latter is energized, to break the toggle. A contact making relay is provided in the circuit 61, the movable auxiliary contact member 65 of said relay is actuated by a solenoid plunger 66 surrounded by windings 67 con-

nected in an electrical circuit of relatively low potential, such as a 12 volt line, including conductors 68 and 80, the latter being grounded to the frame. The conductor 68 is connected with a contact 70 mounted in an insulating block 74 fixed in the stripper plate 17. The contact 70 is arranged to operate with the ram 14 which constitutes a cooperating contact grounded to the frame. The web W of sheet material in its passage 75 between the dies likewise passes between the ram 14 and contact 70, the latter being so located that the scrap portion of the perforated web overlies or passes over the same as it is fed out of the machine. 80

In operation, the machine is started by moving the treadle or operating lever 50 from the dotted position to that position shown in full lines, thus connecting the clutch and causing the shaft 18 to rotate. 85 In so doing the toggle 53 is moved from its dotted line position to that shown in full lines to lock the lever 50 in operative position. Rotation of the shaft 18 causes the ram 14 to move toward and away from the bed, thus causing the dies 15 and 16 to blank out and form articles from the sheet material. The ram at each downward stroke depresses the stripper plate 17 through the interposed web and therefore tends to engage the contact 70, but so long as the perforated portion of the web remains intact and is being properly fed out of the machine it prevents said ram and contact from being brought into engagement. If for any reason the web W becomes broken or displaced, or otherwise fails to be fed or advanced after the last blanking out, the contact 70 is engaged by the ram as the latter is moved towards the bed, thus completing the circuit through conductors 68 and 80, contact 70, ram, and frame and energizing the windings 67 to close the contact 65. Upon closing the contact 65 the solenoid winding 60 is energized to move the plunger 62 against the toggle 53 and move the latter from the full line position to the dotted line position, whereupon the spring 52 moves the lever 50 to its inoperative position and disengages the clutch 35, thereby stopping the machine. 100

What I claim is:

1. In a machine having relatively movable die members for die stamping articles from sheet material, means for feeding sheet material between said members, mechanism for relatively moving said members toward and away from each other, and means for starting and stopping said mechanism, the combination therewith of a stripper plate 120 yieldingly mounted on one of said die members, mechanism for automatically actuating said last-named means to stop the machine including an electrically actuated device, a circuit through said device having a 125

contact carried in an insulated mounting in said stripper plate and a conductor connected to the other die member.

2. In a machine having relatively movable die members for die stamping articles from sheet material, means for feeding sheet material between said members, mechanism for relatively moving said members toward and away from each other, and an operating lever movable for starting and stopping said mechanism, the combination therewith of resilient means normally holding said lever in an inoperative position, means for locking said lever in an operative position, an electrically actuated device for actuating said locking means to release said lever, a high potential circuit through said device containing a movable contact, a low potential circuit for actuating said contact and having contacts adapted to move relatively with said die members to be connected by failure of the web of sheet material to be advanced.

3. In a machine having relatively movable die members for die stamping articles from sheet material, means for feeding sheet material between said members, mechanism for relatively moving said members toward and away from each other, and an operating lever movable for starting and stopping said mechanism, the combination therewith of resilient means normally holding said lever in an inoperative position, a toggle adapted to lock said lever when moved to an operative position, and mechanism for automatically moving said toggle to unlock said lever including means maintained inoperative by the web of sheet material adapted to be actuated by failure of said web to be advanced.

4. In a machine having relatively movable die members for die stamping articles from sheet material, means for feeding sheet material between said members, mechanism for relatively moving said members toward and away from each other, and an operating lever movable for starting and stopping said mechanism, the combination therewith of resilient means normally holding said lever in an inoperative position, a toggle adapted to lock said lever when moved to an operative position, mechanism for automatically moving said toggle to unlock said lever including an electrically actuated device, a circuit through said device having spaced contacts adapted to receive therebetween the web of sheet material, and means for bringing said contacts into engagement upon failure of said web to be advanced.

In testimony whereof I affix my signature.

WILLIAM C. JAY.
